UNITED STATES PATENT OFFICE.

GUSTAV EGLOFF AND HARRY P. BENNER, OF INDEPENDENCE, KANSAS, ASSIGNEES TO
UNIVERSAL OIL PRODUCTS COMPANY, OF CHICAGO, ILLINOIS, A CORPORATION OF
SOUTH DAKOTA.

PROCESS OF TREATING OIL.

Application filed August 20, 1920. Serial No. 404,902.

To all whom it may concern:

Be it known that we, GUSTAV EGLOFF and HARRY P. BENNER, citizens of the United States, and residing in the city of Independence, county of Montgomery, and State of Kansas, have invented certain new and useful Improvements in Processes of Treating Oil, of which the following is a specification.

- 10 This invention relates to improvements in process for treating hydro-carbon oil, and refers to one more particularly adapted in cracking of petroleum oils and petroleum residues. Among the objects of the invention are to provide a process for cleansing the vapors as they pass out of the still or heating zone; to provide a process of the character referred to in which the vapors are preferably subjected to this cleansing action prior to reflux condensation; to provide a process in which the vapors are subjected to said cleansing action while in superheated condition, thereby obtaining more effective and more rapid cracking in the presence of said filtering material; to provide a simple and effective apparatus for carrying out said process, and in general to provide improvements of the character referred to.
- 20

- 30 In the drawings, Fig. 1 is a view partly in side elevation and partly in section of our improvement in said apparatus. Fig. 2 is a cross-sectional view of an enlarged scale taken through lines B—B of Fig. 1. Fig. 3 is an enlarged plan view of the foraminated filter plate taken on lines A—A of Fig. 1.

- 40 Referring to the drawings, 1 designates the furnace, provided with burner 2, bridge wall 3, flue 4, stack 5. In this furnace is mounted a still which in the present instance takes the form of two superimposed spaced cylinders 6 and 7, connected to each other through conduits 8. The shell members 6 and 7 are provided with man hole plates 9, 10 and 11, and with liquid draw off pipes 12, controlled by valve 13. Oil is fed to the

still from the charge pump 14 by means of line 15, connected to the perforated delivery pipe 16, which extends through the upper drum 7, as shown. A valve 17 is interposed in the delivery line 15. Vapors pass out of the still through the conduits 18 to a dephlegmator 19. The upper end of the pipe 18 is provided with a spaced cap member 20, the arrangement being such as to permit the vapors passing into the dephlegmator to prevent the reflux condensate from returning to the pipe 18. The reflux condensate is returned to the still through the line 21, in which is interposed a check valve 22. The pipe 21 is also provided with throttle valve 23. Vapors pass out of the upper end of the dephlegmator through line 24, controlled by valve 25 to condenser coil 26, seated in water condenser box 27. Condenser coil 26 is connected to receiver 28, which receiver is provided with liquid draw off pipe 29, having throttle valve 30 and gas outlet pipe 31, having control valve 32. This receiver also has liquid level gauge 33 and pressure gauge 34.

45 Describing now more particularly the important features of our invention, in the upper part of the drum 7 is positioned and 75 suitably supported as shown a filter support or foraminated filter plate 35, which plate extends throughout the length of the drum and is riveted on bracket supports 36. The apertures or openings in this filter plate are 80 preferably closed by wire mesh 37. The plate is covered with a relatively thick filter bed 38, which may be fuller's earth, bone-black, animal charcoal, cocoanut charcoal or other analogous filling material. This bed 85 may be from a foot to eighteen inches in thickness, and in fact, if desired, the entire upper part of the drum 7 may be filled with this filtering material. The thickness of the filter bed will depend upon the type of oil 90 that is being cracked. For example, if heavy oils, as the California or Mexican oils, are being cracked, it will probably be desirable to have the filtering bed relatively

2

deep for the reason that these oils produce more carbon and sulphur compounds than do Eastern oils. It is desirable that this filtering bed prevent such sulphur 5 pounds and colloidal carbon content from passing out with the vapors. We have discovered that where gas oil from California crude petroleum is cracked, that the pressure distillate, instead of being a normally yellow 10 low color, is deep wine red, indicating the presence of undesirable constituents. By using this filtering bed, we have been able to produce pressure distillate from California gas oil of the usual very light yellow 15 color. It is well known to those skilled in the art that the pressure distillate obtained from the cracking of Kansas or Oklahoma gas oils by the usual commercial method now in use, is of a yellowish color and precipitates a resinous material in the storage 20 tank. By causing the vapors obtained from the cracking of this Kansas or Oklahoma gas oils to pass through our filter bed, preferably while in superheated condition, a 25 nearly water white pressure distillate may be obtained, and which, upon standing, does not deposit this resinous matter. The production of substantially water white pressure distillate obviates the necessity of subjecting the pressure distillate to the usual 30 sulphuric acid, caustic soda and water wash treatments to produce water white gasoline and kerosene.

The process may be carried out as follows: 35 California gas oil of 24 Baumé gravity may be fed into the still and heated to an oil temperature of 740 deg. F., and subject to a vapor pressure of 105 pounds to the square inch. All of the vapors must pass 40 through the filter bed before they leave the still, thus removing the impurities therein, such as those previously referred to. Because of the peculiar arrangement of the still here shown, these vapors are superheated in their passage through said filter 45 bed, it being noted that the vapor space of the still is directly subjected to the action of the products of combustion in the furnace. The pressure may be maintained in 50 the entire system by opening the valve 25, or a pressure may be maintained only in the still and dephlegmator by regulating the valve 25 and by opening the valves 30 and 32, or a differential pressure may be maintained in the system, as for example, 105 55 pounds on the still and dephlegmator and 50 pounds in the condenser and receiver, or combustion may take place at atmospheric pressure. Furthermore, a still further differential pressure may be obtained by placing a valve 25' in the conduit 18. In such 60 case, a pressure of 200 pounds might be maintained on the still, 100 pounds in the dephlegmator, and 50 pounds or atmospheric pressure on the condenser. In any

event, the vapors must pass through the filter bed before they leave the system. Carrying out the process in the manner first referred to, 55% of the California gas oil in question may be converted into pressure 70 distillate of 52 Baumé gravity, producing 32% of gasoline of 58 Baumé gravity, having an initial boiling point of 110 deg. F., and an end point of 435 as determined by the United States Bureau of Mines, standard method. The 32% referred to is based 75 on the original 32% of the total gas oil treated.

We claim as our invention:

1. A process of treating hydrocarbon oils, 80 comprising introducing a supply of oil to a still, in heating the still, in passing the vapors generated from the oil in the still through a filtering bed located in the vapor space of the still above the oil level and above the oil inlet thereto, in subjecting the vapors to dephlegmation in discharging uncondensed vapors and in returning reflux condensate to the still below the filter bed.

2. A process of treating hydrocarbon oils, 85 comprising introducing a bulk supply of oil to a still and subjecting the same to heat, in passing the vapors generated from the oil in the still through a filter bed in the vapor space of said still located above the oil inlet to the still, in discharging vapors that pass through the filter bed from the still into a reflux condenser, and in returning the reflux condensate to the still below

90 said filter bed.

3. A process of treating hydrocarbon oils, 95 comprising introducing a bulk supply of oil to a still and subjecting the same to heat, in passing the vapors generated from the oil in the still through a filter bed located in the vapor space of the still above the oil inlet to the still, in discharging vapors that pass through the filter bed into a reflux condenser, and in returning the reflux condensate to the still below said filter bed, and in maintaining a super-atmospheric pressure 100 on the oil undergoing distillation in the still.

4. A process of treating hydrocarbon oils, 105 comprising introducing a supply of oil to a still having communication with a second still located adjacent thereto, in applying heat to both of said stills to vaporize the oil therein, in passing the generated vapors produced in said stills through a bed of filtering earthy material overlying the feed to said first mentioned still and in discharging the vapors that have passed through said filtering bed into a dephlegmator, in returning the reflux condensate to the first mentioned still below said filtering bed, and in maintaining a super-atmospheric pressure 110 on the oil undergoing distillation.

5. A process of treating hydrocarbon oil, 115 consisting in maintaining a bulk supply of

oil at a conversion temperature in an enlarged zone, in passing the vapors generated from the oil in the enlarged zone through a filter bed in the vapor space of said enlarged zone, in discharging vapors that have passed through the filter bed from said enlarged zone to a reflux condenser, in returning re-

flux condensate separated from the vapors to a point below the filter bed to be again subjected to a conversion temperature, and in maintaining a superatmospheric pressure on the oil undergoing treatment.

GUSTAV EGLOFF.
HARRY P. BENNER.
